UNITED STATES PATENT OFFICE

2,276,865

PRESSURE MEANS FOR WRINGER ROLLS

Julian L. Perkins, West Springfield, Mass., assignor to Perkins Machine and Gear Company, West Springfield, Mass., a corporation of Massachusetts

Application December 20, 1940, Serial No. 370,995

6 Claims. (Cl. 68—262)

This invention relates to improvements in wringers and is directed more particularly to a tension or pressure mechanism for the rolls of wringers.

The principal objects of the invention are directed to the provision of novel means for tensioning the rolls of a wringer or putting the wringer rolls under tension so that they apply pressure to material passing through the said rolls.

Various novel features and advantages of the invention will be hereinafter more fully referred to in connection with the accompanying description of the preferred form of the invention, reference being had to the drawings wherein:

Fig. 1 is a partial side and longitudinal sectional elevational view of a wringer embodying the novel features of the invention; and

Fig. 2 is a transverse sectional elevational view on the line 2—2 of Fig. 1.

Referring now to the drawings more in detail, the invention will be fully described.

A wringer head is represented at 2 and an end frame member is represented by 4 which may be connected together in any suitable manner as by a longitudinal member 6 to form a wringer frame structure.

A lower roll 8 has one end portion of its shaft 10 journaled in a bearing 12 and its other end 12 is operatively connected to a roll drive shaft 16.

The head 2 may contain reversing gearing held in this lower position and this may be called any well known form for driving the shaft 16 at initial tension. The roll 28 and hub 26 of the bearing 18 of the head is shown in which there is an operating member 22 are shown in Fig. 2 as they are bushings for supporting the shaft 16. These are positioned when the operating member is in reversing gearing forms no part of the present invention and therefore need not be described.

it being understood that shaft 16 is driven for driving shaft 12.

An upper frame 22 commonly called an operating member carries an upper roll 24 for coating with the lower roll 8. This roll 24 has the ends of its shaft journaled in hubs 26 at opposite ends of the operating member 22. Roll 24 is either side thereof.

28 are journalled in the ends of the operating member 22 which with the hubs 26 releasably lock the operating member to receivers 30. The receiver 30 one in the head 2 and one in the end frame 4 are similar so that the one associated with the head only need be described.

As shown in Fig. 2, the receiver 30 at its upper end is provided with a vertically disposed slot 32 leading into recesses 35 having cam surfaces 34. A lower recess below part 26 is indicated by 36.

A lower vertically disposed slot is provided in the receiver which is of a width substantially equal to the diameter of the bearing 18 so that the receiver may move up and down, all as shown in Fig. 2. As stated, there is a receiver associated with frame end 4 and formed similarly to that

55 slightly against the action of the springs. The springs, rolls, and cam surfaces act to releasably lock the operating member in an operative position with the upper roll on the lower roll.

In this position the receivers may move upwardly against the action of the spring when material, such as clothes, is passed between the rolls so that the springs apply pressure to the rolls and material passed therebetween.

From the foregoing it will be observed that the pressure applied to the rolls may be varied

by moving the central part of the springs towards and away from one another. The mechanism is simple in form and adapted to facilitate small variations in pressure within a wide range of pressures.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A wringer comprising in combination, a main frame having a roll journalled therein, an upper frame carrying a roll for coacting with said lower roll which is swingable between a central inoperative position to operative positions at the sides thereof, receivers slideable up and down at opposite ends of the wringer, releasable locking means associated with the opposite ends of the upper frame and receivers to facilitate releasably locking the said upper frame to the receivers in an operative position, pressure applying means including separate longitudinally extending springs having their opposite ends seated in the main frame and receivers respectively and a member holding the central portions of said springs against separation, and means connecting the said upper and lower springs to vary the tension thereof and limiting the spread of said springs at opposite ends thereof.

2. A wringer comprising in combination, a main frame having a roll journalled therein, an upper frame carrying a roll for coacting with said lower roll which is swingable between a central inoperative position to operative positions at the sides thereof, receivers slideable up and down at opposite ends of the wringer, releasable locking means associated with the opposite ends of the upper frame and receivers to facilitate releasably locking the said upper frame to the receivers in an operative position, upper and lower longitudinally extending springs with opposite ends of one spring seated in the main frame and opposite ends of the other spring seated in the receivers, and means holding the central part of the springs against separation and tending to force the ends thereof apart including an adjusting bolt extending through said springs.

3. A wringer comprising in combination, a main frame having a roll journalled therein, an upper frame carrying a roll for coacting with said lower roll which is swingable between a central inoperative position to operative positions at the sides thereof, receivers slideable up and down at opposite ends of the wringer, releasable locking means associated with the opposite ends of the upper frame and receivers to facilitate releasably locking the said upper frame to the receivers in an operative position, pressure applying means including separate longitudinally extending upper and lower springs with spaced apart central and end portions with the latter seated in said main frame and receivers respectively said springs including portions directly contacting each other at either side of the central portions, and means acting on the said central portions of the springs to draw them together and in con-

junction with the contacting portions to spread the ends of the springs and vary the action of the end portions thereof.

4. A wringer comprising in combination, a main frame having a roll journalled therein, an upper frame carrying a roll for coacting with said lower roll which is swingable between a central inoperative position to operative positions at the sides thereof, receivers slideable up and down at opposite ends of the wringer, releasable locking means associated with the opposite ends of the upper frame and receivers to facilitate releasably locking the said upper frame to the receivers in an operative position, pressure applying means including separate longitudinally extending upper and lower springs with spaced apart central and end portions with the latter seated in said main frame and receivers respectively and abutting portions at either side of the central portions, and means acting on the said central portions of the springs to draw them together and in conjunction with the abutting portions to spread the ends of the springs and vary the action of the end portions thereof, said latter means acting on the central portions of the springs including a bolt extending through the springs.

5. A wringer comprising in combination, a main frame having a roll journalled therein, an upper frame carrying a roll for coacting with said lower roll which is swingable between a central inoperative position to operative positions at the sides thereof, receivers slideable up and down at opposite ends of the wringer, releasable locking means associated with the opposite ends of the upper frame and receivers to facilitate releasably locking the said upper frame to the receivers in an operative position, pressure applying means including separate longitudinally extending upper and lower springs with spaced apart central and end portions with the latter seated in said main frame and receivers respectively and abutting portions at either side of the central portions, means acting on the said central portions of the springs to draw them together and in conjunction with the abutting portions to spread the ends of the springs and vary the action of the end portions thereof, and means limiting the spread of the end portions of the springs.

6. A wringer comprising in combination, a main frame having a roll journalled therein, an upper frame carrying a roll for coacting with said lower roll which is swingable between a central inoperative position to operative positions at the sides thereof, receivers slideable up and down at opposite ends of the wringer, releasable locking means associated with the opposite ends of the upper frame and receivers to facilitate releasably locking the said upper frame to the receivers in an operative position, pressure applying means including separate longitudinally extending upper and lower springs with spaced apart central and end portions with the latter seated in said main frame and receivers respectively and abutting portions at either side of the central portions, means acting on the said central portions of the springs to draw them together and in conjunction with the abutting portions to spread the ends of the springs and vary the action of the end portions thereof, said latter means acting on the central portions of the springs including a bolt extending through the springs, and means limiting the spread of the end portions of the springs including bolts extending through said springs.
